UNITED STATES PATENT OFFICE.

BENJAMIN H. ALVEY, OF LOUISVILLE, KENTUCKY, ASSIGNOR TO THE ALVEY-FERGUSON COMPANY, OF LOUISVILLE, KENTUCKY, A CORPORATION OF KENTUCKY.

CONVEYER.

No. 881,042.

Specification of Letters Patent.

Patented March 3, 1903.

Application filed August 6, 1907. Serial No. 387,265.

To all whom it may concern:

Be it known that I, BENJAMIN H. ALVEY, a citizen of the United States, residing at Louisville, in the county of Jefferson and 5 State of Kentucky, have invented certain new and useful Improvements in Conveyers, of which the following is a specification.

This invention relates to certain improvements in carriers or conveyers, and particularly to the type thereof, shown, for example, 10 in my Patent Number 790,811 granted May 23, 1905, in which packages are propelled along a way having rollers for the packages to travel upon, by an endless traveling 15 means having propelling or pushing devices to engage the packages and communicate movement thereto on said rollers.

In these conveyers, it is found that the 20 pushing devices are liable to get under the packages at the receiving end of the conveyer, and are not properly propelled thereby along the way, but, on the contrary, are dragged or carried a short distance and then allowed to fall back, the disadvantage of 25 which is apparent. To reduce this liability, the patent referred to disclosed propelling devices in the form of rotatable flights or carriers. Among the important advantages of 30 these flights or carriers is their adaptability to turn freely on their shafts and travel from beneath packages which are not properly positioned in front of the same, without carrying such packages onto the way or around the sprocket by which the endless 35 chains carrying said flights are propelled.

While in many cases the flights or carriers referred to satisfactorily accomplish the purpose referred to, yet in some cases they have been found to be unsatisfactory in this respect. My present invention therefore 40 contemplates the provision of a conveyer with means which project into the path of travel of packages so as to be engaged by said packages, and as a principal function thereof are 45 adapted to retard or resist the movement of packages which are not properly engaged with the propelling means of the conveyer, sufficiently to hold such packages against movement with the propelling means, and 50 are further adapted to permit movement with the propelling means of packages which are properly engaged by the latter. The means referred to, as herein shown and as

preferred, comprise a pair of arms which project toward each other, diagonally into 55 the way or path of travel of the packages from opposite sides of the way and control the movement of packages on the way. They have sufficient rigidity to resist direct 60 onward movement of packages which are not properly positioned on the track or way and are improperly engaged with the propelling means, while they are sufficiently elastic to yield to the pressure of suitably positioned 65 packages which by reason of a proper engagement with the propelling means are being forcibly propelled along the way, such yieldability thereby permitting the packages to pass between the arms.

As herein illustrated this feature of the 70 invention is embodied in a conveyer comprising the features of my patent hereinbefore referred to, and is especially adapted for use with the same, but is not restricted to 75 use therewith.

In my present construction, I have also 80 embodied certain important changes in the construction of the frame of the conveyer, and means for taking up slack in the endless propelling chains.

The invention consists in certain peculiarities in the construction and arrangement of parts, and in certain novel combinations of elements substantially as hereinafter described and particularly pointed out in the 85 subjoined claims.

In the accompanying drawings, I have 90 shown what I at present regard as the best form of the invention but it is distinctly to be understood that the invention is not in its broader aspects restricted to the detail form and arrangement illustrated and that the latter is merely preferred and exemplificatory of one of many different forms and arrangements in which the invention may be embodied without departure from the spirit thereof or from the scope of subjoined claims.

In the drawings:—Figure 1 is a perspective view of the receiving end portion of a conveyer embodying my present improvements. Fig. 2 is a plan view of the conveyer. Fig. 3 is a side elevation of the receiving end portion thereof.

The same characters of reference designate the same parts in the several views.

The frame of the conveyer or carrier is

mounted at each end upon suitably arranged supporting legs of which those at the receiving end are designated by the reference letter 1 while those at the delivery end are designated by the reference letters 2. As here shown, the carrier has an upwardly inclined portion A, the one illustrated being intended to convey packages from one floor or level to another. There are four of the legs 1 and they are preferably made of angle irons. They are connected with each other at the sides of the frame by braces 3 which also are preferably made of angle irons. The braces 3 are so formed or disposed as to leave between them, at each side of the frame, a space or opening 5 adapted respectively to receive the bearings 6 of the journals 7 of the sprockets 8 by which the chains 9 of the propeller are moved. The braces 3 also accommodate and support boxes 10 within which the bearings 6 are adapted to be moved to take up slack in the chains 9, and through the end of said boxes screws 11, having wheels 12 or other suitable means for convenience in operating the same, are threaded and engage the bearings 6 and are adapted to move the latter. The boxes 10 and bearings 6 are formed respectively with interengaged guide flanges 10^a and grooves 6^a. The legs 1 are also connected with each other by cross pieces 13, also preferably made of angle iron. The longitudinal sides of the frame, similarly preferably are formed of upper, lower and intermediate angle irons, which may be disposed as in my patented construction aforesaid: that is to say, having, at each side, upper members 14 and 15, arranged with the vertical portions 14^a of one extending downward and the similar portion of the other extending upward from the respective horizontal portions thereof, to form guides for the upper runs of the chains 9; lower members 16 are similarly disposed to form guides for the lower runs of the chains; and intermediate members 18, supporting the transverse freely rotatable rollers 19 and straps 20 which form the floor of the way. The several frame members are suitably connected with each other, as, for example, by straps 21.

It is of the utmost importance that there be no slack or drag in the chains 9 and, therefore, in addition to providing means for taking up slack therein, I have found it necessary to provide means to coöperate with the horizontal portions of the described angle irons, for holding the upper runs of said chains against dragging, or downward movement, at the receiving end of the conveyer. Such means are afforded by the straps or irons 22 located at the sides of the frame and extending from the sprocket 8, longitudinally of the frame, either throughout the entire length thereof, or only to the angle irons 15, if the latter be arranged as in my patented construction referred to. These irons or straps

22 have their upper surfaces approximately in the horizontal plane of the upper surface of the sprockets, so as effectually to support the upper run of the chains against any tendency to drag at the receiving end of the conveyer. Their ends, 23, contiguous to the sprockets 8 are rounded and bent back, whereby they are strengthened at this place and afford no obstruction to the free travel of the chains from the sprockets.

It will be understood that the chains 9 referred to, carry the package-engaging devices. The form of such devices herein shown are similar to those shown in my said patented construction, consisting of rotatable flights or carriers 25 extending across and above the bed of the way from one chain to the other. As already suggested, these flights or carriers are reasonably effective in freeing themselves, by their rotative movements on their axes and their onward movement with the chains, from packages which are upon instead of in front of them. I have, however, as already stated, found it desirable to provide means which will afford resistance to the onward movement of the packages at the receiving end of the conveyer so that such movement of packages which are not properly engaged with the propellers will be absolutely assured. For this purpose I employ a pair of spring arms 26 and 27 which are suitably secured at their forward ends to the frame of the conveyer, as shown at 28, 28, and have their opposite ends free and projecting toward each other into the path of the packages, one of which packages is indicated at X in Figs. 2 and 3. It will be apparent that if a package is being carried upon one of the propelling rollers 25, it will be engaged and held by the spring arms 28 until the roller has passed from beneath it, when it will properly settle upon the bed of the conveyer in position to be properly engaged by the next succeeding propelling roller 25. It will also be apparent that the arms will yield to a package which is being properly propelled and will permit the same to pass between and beyond them.

From the foregoing, the purposes, advantages and operation of the several new features of the present invention will be readily understood and it will further be understood that language used herein, and the drawings, are to be interpreted merely as illustrative and not in a restrictive sense; the invention being susceptible of many apparently widely different variations without departure from the spirit thereof or the scope of subjoined claims.

Having thus described the invention what I believe to be new and desire to secure by Letters Patent, is:—

1. In a conveyer, a package propelling means having traveling devices to engage the packages and force the same along the

conveyer, and means for retarding the movement of packages which are improperly engaged by said propelling means, and to permit the movement of such packages as are properly engaged therewith.

2. In a conveyer, a package propelling means comprising endless traveling chains and devices extending transversely of the conveyer and connecting the chains with each other and adapted to engage the packages, and means for retarding the movement of packages which are improperly engaged by said devices, and to permit the movement of such packages as are properly engaged therewith.

3. In a conveyer, a package propelling means having traveling devices to force the packages along the conveyer, and yieldable arms extending toward each other into the path of the packages and adapted to prevent movement of packages which are improperly engaged by said devices and to permit movement of such packages as are properly engaged therewith.

4. In a conveyer, a frame comprising sides formed to provide guide ways, endless chains which travel in said ways, package engaging devices carried by said chains, and arms extending diagonally into the path of the packages, and adapted to prevent movement of such packages as are improperly engaged with said devices, said arms being yieldable to permit movement of packages which are properly engaged with said devices.

5. In a conveyer, a carrier way provided with spring arms, extending inwardly from the sides thereof, and means for conveying the packages along said way and between said arms.

6. In a conveyer, a carrier way having an inclined portion, means for conveying packages along said way, and yielding retarding means for the packages, arranged at or near the base of the incline.

7. In a conveyer, a carrier way, having an inclined portion, means for conveying packages along said way, and yieldable arms extending toward each other and into the path of the packages, at or near the base of the incline.

8. In a conveyer, a track or way, and arms arranged in the path of movement of packages on said track or way, said arms extending diagonally inward beyond the lateral boundaries of the track or way from opposite sides of the same and in the direction of movement of the packages.

9. In a conveyer, a track or way, an endless traveling means arranged over the track or way and having devices to engage the packages and control the movement of the same on the track or way, and arms between which the packages travel, said arms extending from opposite sides of the track or way, inward beyond the lateral boundaries thereof

in the direction of movement of the packages on the track or way.

10. In a conveyer, the combination with a means for supporting packages, and devices traveling relatively to said means and controlling the movement of packages thereon, of means adapted to restrain the movement of packages until the traveling devices are in position properly to engage the same.

11. In a conveyer, the combination with a means for supporting packages, and devices traveling relatively to said means and controlling the movement of packages thereon, of spring arms projecting into the path of the packages and adapted to restrain the movement of the same until the traveling devices are in position properly to engage the same.

12. In a conveyer, a track or way, an endless traveling means arranged over the track or way and having devices to engage the packages and control the movement of the same on said track or way, and arms arranged in the path of movement of packages on said track or way, said arms extending inward into the track or way from the sides of the same and yieldable to permit packages to pass therebetween which are being forcibly propelled by said traveling means.

13. In a conveyer, a package propelling means having rotatable traveling devices to force the packages along the conveyer, and retarding means in the path of said packages, adapted to prevent movement of packages which are improperly engaged with the propelling devices and to permit movement of packages which are properly engaged with said devices.

14. In a conveyer, a package propelling means having endless traveling chains and rotatably mounted flights or carriers connecting the chains with each other and adapted to engage packages above the bottoms thereof; and yieldable retarding means arranged in the path of the packages and adapted to retard the movement of packages improperly engaged with said flights or carriers.

15. In a conveyer, a package propelling means having endless traveling chains and rotatably mounted flights or carriers connecting the chains with each other and adapted to engage packages above the bottoms thereof; and spring arms extending inclination toward each other into the path of the packages and adapted to retard the movement of packages improperly engaged with said flights or carriers.

16. A conveyer, comprising a frame having a track or way provided with rollers upon which travel the packages being conveyed, a traveling conveying means having roller flights which are engaged above the first mentioned rollers and engage the sides of the packages and push the same along the track.

or way, and a retarding means arranged in the path of the packages, for the purposes specified.

17. A conveyer, comprising a frame having a track or way provided with rollers upon which travel the packages being conveyed, a traveling conveying means having roller flights which are arranged above the first mentioned rollers and engage the sides of the packages and push the same along the track or way, and yieldable arms projecting into the path of the packages, for the purposes specified.

18. A conveyer comprising a frame formed to provide a package-way, an endless traveling means by which the packages are propelled along said way, rotative means at the opposite ends of the way for communicating motion to the endless traveling means, a support for the frame depending therefrom and having a bracing means arranged below said frame and at each side of the support, take-up boxes for the journals of one of the rotative means, slidably mounted upon the bracing means, said bracing means and boxes having interengaged guide-flanges and grooves, and means for adjusting the take-up boxes upon the bracing means.

19. A conveyer, comprising a frame, provided with a floor, endless traveling means having package-engaging devices for propelling the packages along said floor, rotative means for communicating motion to the traveling means, supports for said frame by which the bearings of said rotative devices are carried, one of said supports having its

sides provided with braces relatively disposed to leave a space between them, take up boxes secured to said braces and having an opening registered with that between the same, bearings for the journals of the rotative device slidably mounted in said box contiguous to said opening, and adjusting devices threadably engaged with the ends of the boxes and engaging said bearings.

20. A conveyer comprising a frame, provided with a floor, endless traveling means having package-engaging devices for propelling the packages along said floor, rotative means for communicating motion to the traveling means, supports for said frame by which the bearings of said rotative devices are carried, one of said supports having its sides provided with braces formed of angle irons relatively disposed to leave a space between them, take up boxes secured to said braces and having an opening registered with that between the same, bearings for the journals of the rotative device slidably mounted in said box contiguous to said opening, said boxes and bearings respectively formed with guide grooves and flanges, and adjusting devices threadably engaged with the ends of the boxes and engaging said bearings.

In testimony whereof I affix my signature, in presence of two witnesses.
